KITE STRING WINDER

John G. Kircher, Woodford Road and Ridge Ave.,
Cincinnati, Ohio 45213

Filed Jan. 4, 1968, Ser. No. 10,049

Term of patent 14 years

(Cl. D41—1)

FIG. 1 is a front elevational view of a kite string winder showing my new design;

FIG. 2 is a side elevational view thereof;

FIG. 3 is a rear elevational view thereof;

FIG. 4 is a top plan view thereof;

FIG. 5 is a bottom plan view thereof;

FIG. 6 is another front elevational view thereof, a stop being shown in an alternate position; and

FIG. 7 is another side elevation view thereof.

I claim:

The ornamental design for a kite string winder, as shown and described.
